UNITED STATES PATENT OFFICE

HAROLD J. GOSS, OF NASHUA, NEW HAMPSHIRE, ASSIGNOR TO THE INTERNATIONAL PAPER BOX MACHINE COMPANY, OF NASHUA, NEW HAMPSHIRE, A CORPORATION OF MAINE

MACHINE FOR MAKING PAPER BOXES

Application filed May 30, 1930. Serial No. 457,638.

This invention relates to the manufacture of paper-board boxes, and has particular reference to machines for making rectangular boxes in set up form ready to have goods placed therein. Boxes of such type are referred to as wall boxes for the reason that they present upright side portions which serve as walls to retain goods.

The particular boxes made by the present machine are of a type known as berry boxes the side walls of which are not parallel, but diverge. In fact the present machine is especially adapted to make boxes such as illustrated in Figure 8 of the drawings herewith.

In boxes for containing berries, it is not practical to employ adhesive for holding the overlapped portions together because the moisture of the berries, or the juice thereof or of other fruits, will so soften the adhesive that the boxes lose their shapes. And such adhesive is liable to impart a disagreeable flavor to the fruits. Therefore, one of the objects of the present invention is to provide a machine for automatically making boxes suitable for containing berries or other fruits, the material being paper-board preferably waxed, the said machine having means for securing the overlapped wall members together by metallic fastenings instead of such adhesive as is usually employed for most types of paper-board set-up or wall boxes.

With said object in view, and others hereinafter explained, the invention consists in the construction and combinations of parts substantially as hereinafter described and claimed.

Of the accompanying drawings:

Figure 1 is a side elevation of the machine.

Figure 2 is an end elevation looking from the right of Figure 1.

Figure 3 represents a vertical section on line 3-3 of Figure 2, on a larger scale.

Figure 4 is a plan view of the delivery end of the machine.

Figure 5 represents a detail horizontal section on line 5-5 of Figure 2.

Figure 6 is a detail view of parts of a signalling mechanism hereinafter referred to.

Figure 7 is a plan view of one of the special blanks operated on by the machine.

Figure 8 is a perspective view, partly broken out, of one of the boxes made by the machine.

Figure 9 is a diagram of certain electric connections hereinafter described.

Similar reference characters designate similar parts or features in all of the views.

The frame of the machine is illustrated at 15. A suitable table for a pile of blanks to be acted upon is illustrated at 16 (Fig. 1). From said table the blanks are fed singly and successively by a combing wheel 17 carried by a shaft 18, said blanks then passing between upper and lower guide strips 19, 20, and onto a pair of carrier chains 21 having spaced pins 22 to engage the rear edges of the blanks to carry them along to the folding and stitching mechanism of the machine. The 70 chains 21 are mounted on sprockets carried by the shafts 23, 24. The mechanism as so far described is practically the same as in Letters Patent No. 1,563,184, issued to me November 24, 1925, and therefore detailed 75 description and illustration thereof, and the driving mechanism therefor, is unnecessary herein. Also certain blank pushing members utilized in the machine of said patent are employed herein and form no parts of the 80 mechanism claimed herein.

As the machine is designed especially to convert blanks such as illustrated by Figure 7, to the set-up box form illustrated by Figure 8, the blank and box will now be briefly described before proceeding with the description of the machine.

The blanks are cut and creased so that each has a central portion *a* (Fig. 7), two opposite wall sections *b* with foldable edge flaps *c*, and two opposite wall sections *d* each having flaps *e*. Usually the longitudinal margins of the wall sections *d* are doubled as indicated in Figure 7, but this is not essential. Preferably the blanks are slotted as at *f* so that when folded or set up (Fig. 8) the slotted portions will provide short legs extending below the bottom of the box. The stitches or wire staples as hereinafter described are applied as indicated at *g* in Figure 8.

Returning to Figure 1, each blank fed by the combing wheel 17 and being carried along by a pair of pins 22 of the two chains, is first acted upon by a pair of side guides 25, one of which is illustrated in Figure 1, to ensure travel of the blank in squared up condition. Then the two edge flaps *c* are broken down on their crease lines by a pair of revolving segments 26 carried by shaft 27. Next, the flaps *e* are broken down by the revolving duplex arms 28 of the shaft 29 to a somewhat further extent than the flaps *c* were turned down, and said flaps *e* are directed by the said arms 28 to the inner sides of the two converging rods 30 (Figs. 1 and 4). Said rods 30 are 10 adjustably mounted in order that they may be secured in fixed positions to ensure breaking of the flaps *e* down to a nearly vertical position as they travel. The longer but narrower flaps *c* however, which have been 15 partly broken by the segments 26, merely to ensure later correct folding on their crease lines, pass along above the rods 30, (Fig. 1).

For the correct operation of the machine it 20 is important that all parts thereof shall operate at proper relative times, and of course the driving and gearing mechanism is mechanically designed to provide for proper timing of the folding and stitching mechanisms 25 relatively to the timing of the blank feeding mechanism and the speed of travel of the blanks being fed and carried to the folding and stitching mechanisms. Such time gearing is well known in machines of 30 this general type and therefore detailed illustration and description thereof would be superfluous herein. For some reasons however, especially when the blanks are coated with waxy material, it will sometimes happen 35 that a blank does not travel along in correct time. To announce any blank that is moving along out of time, I provide a safety device 40 consisting of a light lever 31 which, as will be presently explained, acts as a switch to effect an alarm if a blank is travelling along 45 to the folding and stitching mechanisms out of time. Said lever 31 is mounted, properly insulated, in a block 32 pivotally supported on a rod 33 and having one end bent in at 34 50 (Fig. 4) and having a downwardly inclined tip 35 (Figs. 1 and 9), said inclined tip 35 normally extending slightly across the plane of travel of every blank flap *c*. The other end 55 of the lever 31 is bent to extend over a grounded notched disk 37 carried by the shaft 24 which rotates once for each blank being fed. The lever 31 is electrically connected with one end of an insulated wire 38 which, through connections to be described, 60 effects an alarm so that the attendant can stop the machine.

The lever 31 is so mounted that it may rock freely but with its longer end down so that its inclined tip 35 will be acted upon by every 65 passing blank and lifted. If every blank

passes said tip 35 and rocks or tilts the lever while the recess or notch in the revolving disk 37 is uppermost, the other end 36 of the lever simply enters the said recess and nothing happens. But if a blank is travelling out of 70 time and passes the tip 35 of the lever while the larger diameter of the grounded notched disk 37 is under the end 36 of the lever, contact is made between said lever and disk and the circuit is completed through a portion 75 of the lever 31, the wire 38 and other connections presently described, to ring a bell 39 (Figs. 2 and 9).

The wire 38 is connected to a bell-ringing transformer 40 having another connection 41 80 with the bell and having connections 42, 43, with a suitable electric power line. The bell has a suitable ground connection 44.

I do not limit myself to the employment of an alarm bell to notify an attendant to stop 85 the machine, as any well-known electrically-operated mechanism for effecting automatic stoppage of the machine may be substituted therefor.

Each blank pushed to position to be operated upon as presently described, enters between two side guides 45 (Figs. 2, 3, 4 and 5), and is arrested by stops 47 supported by a tie rod 46.

Plunger mechanism for operating in an 90 upward direction on each blank consists of members similar to the duplex plunger mechanism of the Patent No. 1,563,184 hereinbefore referred to. The upper form 48 (Figs. 2 and 3) has its stem or shank 49 guided between the two members of the stem of the lower plunger presently described, said stem 49 being connected by a link 50 with an arm 51 of a rock shaft 52, the latter having another arm 53 carrying a roll bearing against 95 a cam 54 secured to shaft 55. The lower form 56 has its duplex stem 57 mounted in suitable slideway bearings, said stem members being connected by links 58 with arms 59 of a rock shaft 60, the latter having another 100 arm 61 carrying a roll bearing against a cam 62 secured to the shaft 55.

To operate as presently described, two upright tucker plates 63, having inwardly bent upper ends (Figs. 2 and 3), are carried by 105 rods or stems 64 projecting inwardly from the upper ends of two arms 65 pivoted at 66 to blocks mounted on a tie rod 67. A spring 68 connects the two arms 65, and each arm has a small roll 69 acted upon by a recess-faced cam 70 carried by the shaft 71.

The upright forming chamber comprises four strips 72 angular in cross section (Figs. 1, 2, 3 and 4), said strips being rigidly supported by brackets 73 mounted on tie rods 74. Said strips have openings 75 through which the four stitchers hereinafter referred to operate. Above said openings (Fig. 3) is a slide 76 mounted to reciprocate in one of the brackets 73 and connected by a link 77 with 115

the upper end of a lever 78 secured to a rock shaft 79 mounted in hangers 80 fixed to and depending from the tie rod 46. The rock shaft 79 has an arm 81 provided with a roll 82 which is acted upon by a cam 83 carried by the shaft 71. Said cam acts to shift the slide 76 outwardly at the proper times, while a spring 84 connecting the arm 81 with a suitable fixed point effects inward movement of the slide to temporarily provide a limit to which a blank that is being operated upon can be elevated in the forming chamber, as presently described. The operation of the plunger forms will now be described before 15 describing the stitchers:—

When a blank arrives against the stops 47, its central portion *a* is above and registers with the surface of the upper plunger form 48 which then rises into the forming chamber 20 to a height that carries said central portion *a* of the blank practically against the slide 76 which is then in the position illustrated in Figure 3. During such movements, the wall sections *b*, *d*, of the blank are turned on their broken crease lines in a downwardly folded direction due to their contact with the lower edges of the chamber sections 72. During such movement the flaps *e*, which as has 25 been described had been broken quite far down by the actions of the rotary arms 28 and the converging rods 30, swing in so that the sections *b* fold outside of said flaps *e*. But the narrow edge flaps *e*, although somewhat broken on their crease lines, are still 30 pendant. The tuckers 63 now move in and swing the flaps *c* in far enough so that they will be engaged by the now rising lower plunger form 56. The tuckers retreat as the 35 form 56 continues to rise, said form then folding the flaps *c* snugly against the inner surfaces of the flaps *e* (Fig. 8) ready for the stitching to be effected as presently described. During the upward movement of the lower form 56 the temporary presence of the slide 40 76 in the position illustrated in Figure 3 prevents the partly folded blank on the upper form 48 from being pushed up away from the latter by the entrance of the lower form into said blank to complete the folding.

As illustrated by Figure 4, the slide 76 is not wide. Therefore, to somewhat supplement its box-arresting function, I provide two small rolls 85 in opposite spaces in the sides of the forming chamber (Figs. 3 and 4), each roll being carried by a frame or arm 86 pivotally mounted on a cross pin 87. Suitable springs such as illustrated at 88 in Figure 1 are employed to cause the two opposite rolls 85 to yieldingly occupy positions slightly within the area of the forming chamber so that opposite bottom corners of the inverted box will contact with said rolls, the latter thereby resisting tendency of the box to be pushed up before the stitching operation is effected. After such stitching operation the

slide 76 is shifted outwardly, and when a completed box is being later pushed up through the forming chamber, the rolls 85 yield to permit it to pass. The rolls are short and so located that when a box is rising, the 70 leg members of the latter pass without contact with said rolls and therefore are not injured thereby.

There are four stitcher heads 89 (Figs. 2 and 4) which operate through the openings 75 75 in the forming chamber 72 (Fig. 3). The details thereof, including the wire feeding and the cutting and shaping of the wire are so well-known that illustration and description of such details are unnecessary herein. 80 Said mechanism employed in the present machine is the well-known "Bostitch".

Each head 89 is supported by a bracket 90 mounted on tie rod 74. The heads are adjustably mounted independently to vary their 85 distance apart to suit different sizes of boxes, and are adjustable tiltably to suit the angle or slant of the side walls of the box according to the shapes of the boxes. And of course different shapes of plunger heads or forms 90 48, 56, may be employed for the making of boxes of different sizes and shapes as to the slant of the side walls.

The wire *x* for each stitcher is supplied from a reel 91 mounted on a bracket 92 suitably supported by the frame of the machine, and leads along a flexible guide 93 to the actuating mechanism of the stitcher, and the two stitcher mechanisms at each side of the machine (Figs. 1 and 2) have actuating rods 94 connected with the upper end of a lever 95.

Each lever 95 is duplex, its members being secured to a rock shaft 96 having an arm 97 provided with a roll bearing against a face cam 98 of the shaft 55. To impart inward movement to the stitchers, when permitted by the cams 98, each lever 95 is actuated inwardly by a spring 99 connected at its inner end to a suitable fixed part of the machine and at its outer end to a pin 100 projecting 110 outwardly from the lever. As illustrated in Figure 2, the inner ends of the two springs 99 are connected to the upper ends of upright fixed arms 101 secured to the tie rod 67.

To cooperate with the stitching mechanisms carried by the stitcher heads 89, anvil blocks 102 are mounted on the sides of the lower plunger form 56. In practice, said anvil blocks are adjustably mounted on said form 56 to properly cooperate with the mechanism of the stitcher heads when the latter are adjusted.

The time of operation of the stitchers is when the lower plunger form has followed the upper plunger form into the forming chamber and the blank has been completely converted to the set-up box condition illustrated by Figure 8 in which figure the stitches also are illustrated at *g*. After the box has been stitched, it remains frictionally in the 120 125 130

forming chamber and is pushed upward in the latter when the next box is formed and stitched. The boxes nest one within another in the chamber 72 and when a number of them 5 protrude from the top of said chamber they are removed by an attendant.

To enable the machine to be stopped if any one of the wires α fails to feed correctly, I provided the following mechanism or devices:—Mounted on the brackets 90 are small blocks 103 of insulating material (Fig. 6) there being four of them as illustrated in Figure 4. A finger 104 is pivotally supported at 105 on one of the insulating blocks 103 at each 15 side of the forming chamber (Fig. 4), and the other end of the finger has a screw 106 bearing on the other block 103 of the pair. Mounted in each finger 104 and extending 20 downwardly therefrom are two pairs of detector wires 107, each pair of said wires terminating at opposite sides of the normal position of a stitching wire α and slightly spaced therefrom (Fig. 6). Each finger 104 is connected by a conducting wire 108 with the wire 25 38 (Fig. 9).

Normally the stitching wires are straight where they pass along through the stitcher heads 89 and there will be no contact with either of the detector wires 107. But if a wire α breaks or otherwise fails to feed correctly, 30 it will make contact with one or the other of the adjacent detector wires and close the circuit through the finger 104 and the wire 108 and the other connections illustrated in Figure 9 and hereinbefore described, and ring the bell 39. This is because the stitching wires α are grounded by the parts of the machine through which they travel. The reason for 35 the fingers 104 being pivoted is to enable 40 either of them to be lifted up to facilitate access to any wire α that needs attention before resuming operation of the machine.

In order that the machine may continue to run but the stitchers prevented from operating if no folded blank is in the forming chamber in position to be stitched, I provide the following mechanism:—A finger 109 (Fig. 3) secured to a rock shaft 110, extends from said shaft in an upwardly inclined direction 45 through the space between two of the angular sections of the forming chamber, the upper end of said finger being curved to offer no appreciable resistance to the upward passage 50 of a box. The rock shaft 110 extends across 55 the width of the machine and has an arm 111 at each end (Figs. 1 and 2) said arms being movable as presently described to serve as obstacles to the inward movement of the stitchers. As has been explained, the inward 60 movement of the stitchers is effected by the springs 99. As shown in Figure 1, a cross bar connects the two lever members 95. A stop pin 112 projects inwardly from said cross bar. This structure is duplicated at 65 both sides of the machine (Fig. 2). As illus-

trated by comparing Figures 1, 2 and 3, every folded blank arriving in the forming chamber in position to be stitched will swing the finger 109 outwardly and, through the rock shaft 110, swing the arms 111 up above the 70 line of inward movement of the stop pins 112 carried by the stitcher actuating lever. But if there is no folded blank in the forming chamber to be acted upon by the next inward movement of the stitcher heads, the finger 75 109 remains in the inward position shown in Figure 3 and the arms 111 of the rock shaft remain down as in Figure 2 so that, although the machine may be still under power, said arms 111 will be in positions to serve as obstacles against which the stop pins 112 will abut, and arrest the operation of the stitchers. But as soon as a folded blank is supplied to its upper position between the openings 75 in the forming chamber, its presence 80 swings the finger 109 out, resulting in the rock-shaft arms 111 shifting up so that the stop pins 112 can not contact therewith. Then the levers 95, which are drawn in by the springs 99 to actuate the stitchers, are 85 free to act.

I do not claim herein the electrical indicating means, as the same forms the subject matter of my divisional application filed September 5, 1931, Serial No. 561,373. 95

Having now described my invention, I claim:—

1. In a machine for making boxes, a forming chamber, upper and lower plungers, 100 means for actuating the upper plunger to cause it to lift a blank into said chamber, tuckers for acting on side portions of the blank, means for actuating the lower plunger to cause it to follow the upper plunger, a slide movable to and from position to cause it to temporarily hold the blank on the upper plunger during the rise of the lower plunger, and stitching mechanism cooperating with the sides of the lower plunger. 105

2. In a box-making machine having a forming chamber, duplex plungers movable into and from said chamber, a slide movable to and from position across said chamber, and yieldably mounted rolls at opposite sides 115 of said chamber above the plane of movement of said slide in position to deter movement of folded boxes in said chamber.

3. In a machine for making boxes, a duplex plunger one member of which is formed to engage the central portion of a blank and the other member has side faces, a forming chamber into which a blank is pushed for folding, and stitching mechanism cooperating with said plunger side faces to secure 120 folded portions of the blank together. 125

4. A machine of the character described having means for folding blanks to set-up form and means for stitching them, means being provided for preventing the operation 130

of the stitching mechanism if no blank is in position to be stitched.

5. A machine for making boxes, said machine having a form and means for folding 5 blanks successively thereon, reciprocating stitching mechanisms at opposite sides of the form, means for delivering blanks to the folding and stitching mechanisms, and means for preventing movement of the stitching 10 mechanisms toward the form during any interruption in the supply of blanks to position to be stitched.

6. A machine for making boxes, said machine having a form and means for folding 15 blanks thereon, reciprocating stitching mechanisms having springs connected thereto to actuate them toward the form, means for delivering blanks successively to the folding and stitching mechanisms, a rock shaft having arms movable to and from position to prevent inward movement of the stitching mechanisms or to permit such movement, and a finger projecting from said rock shaft into the path of travel of the blanks toward position to be stitched.

In testimony whereof I have affixed my signature.

HAROLD J. GOSS.
